WOMAN'S CAPE

Phyllis L. Meyers, 5235 Linwood Drive,
Los Angeles, Calif. 90027

Filed Aug. 11, 1969, Ser. No. 18,619

Term of patent 14 years

Int. Cl. D2—01

U.S. Cl. D2—179

FIG. 1 is a front perspective view of a woman's cape embodying my new design; and

FIG. 2 is a rear perspective view of said cape.

I claim:

The ornamental design for a woman's cape, substantially as shown.
